INVENTOR

UNITED STATES PATENT OFFICE.

WILLIAM HAINES, OF PHILADELPHIA, PENNSYLVANIA.

WATCH.

1,022,078.

Specification of Letters Patent.

Patented Apr. 2, 1912.

Application filed August 25, 1911. Serial No. 646,023.

To all whom it may concern:

Be it known that I, WILLIAM HAINES, a citizen of the United States, residing in the city and county of Philadelphia, State of Pennsylvania, have invented a new and useful Improvement in Watches, of which the following is a specification.

My invention relates to an improvement in a watch or clock which is provided with 10 a device for indicating the condition that the watch or clock is wound or run down such as is shown in the Letters Patent No. 248,310, granted to William Haines and Lewis Breitinger, on the 18th day of October, 1881, the invention therein contained being applied to a key-wound watch.

The present invention consists of means for operating an indicator of the character in a stem-winding watch, the means employed being hereinafter described and the novelty thereof pointed out in the claim.

For the purpose of illustrating my invention, I have shown in the accompanying drawings one form thereof which is at 25 present preferred by me, since the same has been found in practice to give satisfactory and reliable results, although it is to be understood that the various instrumentalities of which my invention consists can be 30 variously arranged and organized and that my invention is not limited to the precise arrangement and organization of these instrumentalities as herein shown and described.

Figure 1 represents a face view of a watch embodying an invention. Fig. 2 represents a view of the watch, the dial having been removed therefrom. Fig. 3 represents a view of a portion opposite to Fig. 2. Fig. 40 4 represents an elevation of a detached portion of the mechanism of the watch. Fig. 5 represents a longitudinal section on line $x-x$ Fig. 2. Fig. 6 represents a section of a portion on line $y-y$ Fig. 2. Fig. 7 represents a section of a portion on line $z-z$ Fig. 2. Fig. 8 represents a perspective view of portion of a detached member. Fig. 9 represents face view of two members of the watch mechanism to be hereinafter referred 45 to. Fig. 10 represents a side elevation of a detached member.

Similar letters of reference indicate corresponding parts in the figures.

Referring to the drawings, A designates 50 the casing of a watch of usual construction.

B designates the dial the same having

thereon the additional dial C over which is the index finger D, to be hereinafter referred to, said dial C having graduations or characters adapted to indicate the condition 60 of the watch whether entirely or partly wound or run down.

E designates the pinion of the stem-winding device of the watch the same being adapted to operate the wheels E. F. on the 65 vibrating arm G usual in stem-winding watches.

H designates a spur wheel which is adapted to mesh with the wheel F and with the wheel J this latter being attached to the arbor K which carries the wheel L. Referring to Figs. 3 and 7, it will be noticed that the wheels J. L. are on opposite ends of said arbor K and the latter passes through the pillow plate K' and the adjacent plate K² 70 of the frame of the watch, the wheel J being on the plate K' and the wheel L on the plate K². The wheel L through the intermediate train of the mechanism, is geared over to the pinion M on the barrel arbor N, 75 said pinion M meshing with the wheel P on whose post Q is the wheel R, the latter meshing with wheel S with which meshes the wheel T, these wheels R, S, T being mounted on the rocking lever or bar U on one end of which is the crook V which is fitted freely on the conical neck V' of the adjacent wheel of the train usual in such cases. One end of said lever has bearing 80 against it the spring V² for restoring said lever to its normal position and retaining it thereat, said spring being held in position by the keeper V³. The wheel T meshes with the pinion W which by intermediate 85 mechanism serves to operate the indicator hand or index finger D hereinbefore referred to, the same being fitted on the sleeve of the wheel R. In the train are the wheel X and ratchet Y shown in Figs. 3, 5, and 9. On said wheel is the pin or stud Z, which is adapted to enter the elongated slot Z' in 90 said ratchet. These features together with the rocking lever U and connected mechanism are well known for preventing back action on said ratchet in unwinding as well 95 known.

It will be seen that when the stem is rotated motion is communicated to the wheels E, F, H, J and consequently to the other members of the train and to the pinion M, whereby the spring is wound, the lever U 100 oscillating and so being disengaged from

and engaged with the pinion W as usual in such cases. With the winding of the spring the wheel R is rotated and the index finger D is carried around with the same thus indicating on the dial C the fact that the watch has been wound-up. As the spring unwinds and the watch runs down, the pinion W communicates motion to the wheels T, S, R, the wheel R now rotating in reverse order to its previous rotation, whereby the index finger D is carried around with the same on the dial C in the direction indicating the fact that the watch is running down and may have run down to full extent or at any intermediate time.

Having thus described my invention what I claim as new and desire to secure by Letters Patent, is:—

In a watch, an arbor, adjacent plates of the watch frame, said arbor being adapted to pass through said plates, wheels on the ends of said arbor, and located respectively on said plates, one of said wheels being adapted to operate an adjacent member of the winding train, stem winding mechanism including a spur wheel which latter is adapted to gear with and rotate the other wheel on said arbor, and indicating mechanism of the wound or unwound condition of the watch, the same being adapted to be operated by said train.

WILLIAM HAINES.
